UNITED STATES PATENT OFFICE.

LEE A. COLLINS, OF LOUISVILLE, KENTUCKY

TELEPHONE-MOUTHPIECE PROTECTOR.

1,140,954.

Specification of Letters Patent. Patented May 25, 1915.

Application filed May 12, 1914. Serial No. 838,129.

To all whom it may concern:

Be it known that I, LEE A. COLLINS, citizen of the United States, residing at Louisville, in the county of Jefferson and State 5 of Kentucky, have invented certain new and useful Improvements in Telephone-Mouthpiece Protectors, of which the following is a specification.

This invention relates to an improved 10 protector for telephone mouthpieces.

The possibility of infection through the use of public telephones is well known since in order to properly talk over a telephone, the mouth must be placed close to the mouth- 15 piece thereof, and thus ample opportunity is afforded for the disease of one user to be transmitted to other users of the telephone either through accidental contact with the mouthpiece or by reason of the fact that 20 the mouth of each user must be brought into such close proximity to the mouthpiece of the telephone.

The present invention accordingly has 25 for its primary object to provide a protector for telephone mouthpieces which will be of such simple construction and consequent low cost that each person may readily provide himself with a protector, and to also provide a device so constructed as to 30 efficiently protect the person using the telephone and so arranged as to be adapted for ready attachment to or detachment from the telephone mouthpiece.

The invention has as a further object to 35 provide a protector which will be constructed of few parts and which will at the same time be adapted for attachment to telephone mouthpieces of different diameters without the necessity of adjustment.

With these and other objects in view my 40 invention will be more fully described, illustrated in the accompanying drawings and then specifically pointed out in the claims which are attached to and form a part of 45 this application.

In the accompanying drawings: Figure 1 45 is a perspective view showing my improved 50 protector applied to a telephone mouthpiece, conventionally shown, Fig. 2 is a vertical sectional view showing the protector applied, Fig. 3 is a perspective view showing the parts of the protector detached but in proper relative position, and Fig. 4 is a vertical sectional view of the protector on 55 an enlarged scale, and especially showing

the arrangement of the diaphragm and the locking ring therefor.

Corresponding and like parts are referred to in the following description and indicated in all the views of the drawings by 60 the same reference characters.

In constructing my improved sanitary telephone mouthpiece I have had in mind the provision of a device of this character which shall be as simple in construction as 65 possible and which shall at the same time be adapted for use under a variety of circumstances, so as to permit the protector to be employed upon telephone mouthpieces of various diameters. 70

In the drawings, the body portion or shell of my improved protector as a whole, is indicated at 10 and may be formed of resilient metal, aluminum, or any other suitable material. The body portion 10 is, generally speaking, a stepped frusto conical shell, the wall thereof having formed therein a series of bands indicated at 11, 14, and 16 which serially increase in diameter toward the base of the shell and are arranged 80 concentric to and parallel with the vertical axis thereof. The bands 11, 14, and 16 are connected by intermediate webs designated 13 and 15 which are also concentric to the vertical axis of the shell and which extend 85 at substantially right angles to such axis, a plurality of mouthpiece engaging seats or pockets being thus provided, each of which is adapted to fit over the peripheral edge of a telephone mouthpiece of a corresponding 90 relative diameter. Formed upon the free edge of the band 11 is an inwardly extending annular flange or shoulder 12 which is arranged to engage a diaphragm as will be presently explained. 95

In Figs. 1 and 2 of the drawings, I have shown my improved protector applied, Fig. 2 more particularly illustrating the manner in which the portions 11, 14, and 16 of the body portion of the protector are disposed 100 to engage the free edge of the mouthpiece. In said Fig. 2, the telephone mouthpiece which is conventionally illustrated at 17 is shown of such diameter as to engage within the outer band 16 as will be readily understood. 105

While I have shown the body portion of the protector as being adapted to engage telephone mouthpieces of three different diameters, still, it is to be understood that the 110

range of use of the device may be greatly enlarged by forming the body portion with a greater number of superposed bands, the wall of the body portion being made longer of course, and I do not wish to limit myself to the particular number of bands and offset portions shown.

The wall of the body portion 10 is preferably instruck as shown to provide a circumferentially extending rib or bead 18 upon each of the vertically arranged portions 11, 14 and 16 and as will be clear, said beads are each so arranged as to engage immediately in the rear of the outer end edge 15 of the telephone mouthpiece when the protector is applied thereto, to thus securely hold the protector in position. In this connection, attention is called to the fact that the side edges of the said beads disposed adjacent the smaller end of the shell provide circumferentially arranged shoulders adapted to bite into the terminal flared outer wall of the mouthpiece to effectually prevent the displacement of 25 the shell since the said shoulders will be held in contact with the outer face of the mouthpiece through the resiliency of the beads and any movement of the shell away from the mouthpiece will bring the said shoulders into secure engagement therewith. It will be observed that the body portion 10 may be readily applied to any mouthpiece of a diameter receivable in one of the rings formed in the wall thereof and may with 35 equal facility be removed. The protector is therefore, adapted to be carried in the pocket to be applied to various telephones as the user may require. I consequently provide a very convenient device and attention 40 is called to the fact that when the protector is applied, in the practical use of the invention, the adjacent band will be caused to expand to resiliently engage the margin of the telephone mouthpiece, the adjacent bead being thus flattened or straightened and brought into close frictional engagement 45 with the mouthpiece. In this manner the protector will be firmly held in operative position.

50 Mounted within the body portion 10 and arranged to seat against the flange 12 thereof is a diaphragm 19. The diaphragm 19 may be formed of mica, paper, or any other suitable material through which sound waves 55 will be readily transmitted, and bearing against the inner peripheral edge of said diaphragm is a locking ring 20. The locking ring 20 is preferably detachably mounted within the body portion 10, being engaged 60 and held in position by the adjacent bead 18. The locking ring 20 is also of such diameter

as to frictionally engage within the adjacent wall of the band 11, to thus more securely hold it in place and by this construction it will be observed that if for any reason the 65 diaphragm 19 becomes broken or it is desired to replace it with a new one, said diaphragm may be readily removed and another one inserted.

It will therefore be seen that I provide an 70 exceedingly simple device for the purpose set forth such as may be readily carried about by the user and which is adapted for ready attachment to or detachment from telephone mouthpieces of various diameters. 75 It will also be seen that the device when applied will efficiently protect the user of the telephone and is thoroughly sanitary in every way since the person using the protector will be the only one coming in contact 80 therewith.

Having thus described my invention, what I claim and desire to secure by Letters Patent is:—

1. A telephone mouthpiece protector including an integrally formed stepped conical shell providing mouthpiece receiving pockets, an inwardly extending annular flange formed on the smaller end of the shell, a plurality of circumferentially disposed and inwardly extending beads struck from the shell, one of said beads being arranged within each of said pockets and disposed to resiliently engage the mouthpiece in the rear of the terminal outer edge there- 90 of for maintaining the shell in engagement with the mouthpiece, a diaphragm disposed within the terminal pocket at the smaller end of the shell and seating against said flange, and a locking ring frictionally engaging within said last mentioned pocket and engaging said diaphragm, said locking ring being engaged by the head of said terminal pocket for maintaining it in position. 100

2. A device of the character described including a support disposed to fit over the flared outer extremity of a telephone mouthpiece, a circumferentially extending and inwardly disposed bead formed on the support and disposed to bear against the outer 110 wall of the mouthpiece, one side edge of said bead providing a shoulder arranged to engage the outer wall of said mouthpiece adjacent the outer terminal end edge thereof, and a diaphragm carried by the support. 115

In testimony whereof I affix my signature in presence of two witnesses.

LEE A. COLLINS. [L. s.]
